UNITED STATES PATENT OFFICE

CARL BRUNO STRANDGREN, OF LE VESINET, FRANCE

TURBINE-WHEEL PROPELLER AND MOTOR

Application filed February 17, 1928, Serial No. 255,160, and in France February 25, 1927.

The present invention relates to turbine wheels provided with feathering or oscillating wings, paddles or the like, which may be used as a propelling and lifting device 5 movable in a fluid, or as a prime-mover actuated by a fluid in motion. The invention relates more particularly to feathering paddle wheels wherein the wings or the like are disposed about a central shaft, around 10 which they are adapted to rotate, each wing being further pivoted on an axis which is parallel to the central shaft, and the oscillation being periodic, the period being equal to that of the revolution on the central shaft. 15 It has been found that such a wheel will operate in the best conditions if the oscillating motion of the wings is so controlled that the normals to the operative surface of the wings or the like constantly cross each other at a 20 fixed point.

The invention has for its object to provide a device which will comply with the above condition.

Another object of the invention consists 25 in providing a control device adapted to control the oscillation of the wings, in such manner as to allow at will any change in the law of oscillation of the wings by varying at will the position of the intersecting point of the 30 normals to the wings.

In the appended drawing, which shows diagrammatically and by way of example a constructional form of the device, employed 35 as a propelling and lifting device for aircraft:

Fig. 1 is a diagram of the device for the control of the oscillations of the wings.

Fig. 2 is a diagrammatical elevational view 40 showing a paddle wheel according to the invention, the device controlling the eccentricity being omitted.

Fig. 3 is a section on a larger scale on the line 3—3 of Fig. 2.

Fig. 4 is a section on the line 4—4 of Fig. 3.

Referring to the diagram of Fig. 1, 5 denotes the central shaft on which is rotatable the paddle wheel, and C denotes the circle described by the pivot pin 7 of each wing 50 15 upon the corresponding arm 14, secured to

shaft 5. A disc 8 is rotatably mounted on rollers 1, 2, 3, so as to roll about the same, that is about a centre 4' distinct from the axis 4 of shaft 5.

The disc 8 is provided with a radial guide 55 or like means 9, and to each arm 14 is pivoted a right-angled rod 10—11, whereof one side 10 is slidable in the guide 9 of the disc, and the other side 11 is pivoted to a link 18 parallel with the arm 14 and whose length is 60 equal to the distance between the pivot pins 7 and 12, said link being pivoted at 13 upon the wing 15. The set of members 11, 14, 15, 18 forms, as may be clearly seen, a deformable parallelogram. The normal 6—7 at 7 to the 65 straight line 7—13, which is parallel with the operative face of the wing crosses the centre line 4—4 at a point 6. It will be seen that the triangles 4—4—12 and 4—6—7 are similar and hence the normal 6—7 to 7—13 will 70 always cross the line 4—4 at point 6, which ever may be the angular position of arm 14 about shaft 5. Point 6 will also be common to the normals to the other wings provided that the pivot pins 7 are all situated on circle C and that the apex 12 of the right-angled bars 10, 11 are all situated on circle C' having axis 4 as a centre.

Fig. 1 shows at 15^a another position of wing 15 after a given rotation, the corresponding positions of the various members being designated by the same reference numerals with the indicia "a".

The wheel shown in Fig. 2 has a star shape 85 and consists of arms 14 carrying the wings or paddles 15, each arm 14 being mounted on a disc 16 keyed to the shaft 5. The construction of the star-shaped body and the wings may be similar to that described in 90 my prior Patent No. 1,639,908 of Aug. 23, 1927. The said arms may consist of steel plate, wood, duralumin metal, or like material, and the outline of their section may be analogous to that of the struts of an airplane cell. The wings 15 are mounted on 95 suitably shaped metal plates 17 which are strengthened at the pivot points. Said plates may have a U section so as to form forked parts straddling over the ends of arms 14 and links 18. Upon a second axle of 100

said forked part is pivotally mounted link 18 which is pivoted at its other end to the small arm 11 of the right-angled rod 10-11. The apex of the various rods 10-11 are 5 mounted upon pivot pins 12 journaled in the disc 16 which is keyed to the central shaft 5, said pins 12 being situated on a common circle C' whose centre is 4.

The discs 8 are mounted upon three rollers 10-12-13, carried by a rectangular metal plate 20, movable in the guides 22-23 of a frame 24. Said frame may be displaced vertically, due to the provision of a slideable connection with a fixed bracket 26. Said 15 displacement may be controlled, for instance by means of a screw 25 engaging a nut 24^a secured to the frame 24, said screw having a smooth shank journaled in a bearing 26^a secured to bracket 26. The screw 28 may 20 be rotated by means of a hand-wheel 27 or by any suitable distant control means. The horizontal displacement of plate 20 with reference to frame 24, may be controlled for instance by means of a screw 28 having a 25 smooth part journaled in a bearing 31 secured to frame 24 and a screwthreaded part engaging a nut 29 slideable on a rod 21 secured to the plate 20. The screw 28 is actuated by a hand-wheel 30 or by any suitable 30 distant controlling means.

In the embodiment shown in Figs. 2 and 3, there are as many discs 8 as there are arms and wings, said discs being laid together and being rotatable on the rollers 1, 2, 3 by 35 concentric and independent rotations. Each disc comprises either a radial guide in which are slideable several studs secured to the rod 10, or, as shown, several studs 32 may be secured to the discs 8 and cooperate with a slot 33 provided on the rod 10.

40 The operation is as follows:

The engine of the aircraft (not shown) drives the shaft 5 by means of a suitable gearing. The star-shaped member shown 45 in Fig. 2 comprising the disc 16 carrying the pivot-pins 12, the arms 14, the wings 15 and the links 18 (which remain parallel to the arms 14) is thus rotated about the axis 4. The motion of the axles 12 and the rods 10-11 50 causes the motion of all the discs 8 about the rollers 1-2-3, but, due to the eccentricity of said discs with reference to the shaft 5, a reciprocating sliding motion is imparted to the studs 32 in the slots 33; the rods 11 55 are thus oscillated on the pins 12, and the wings, which are connected with the rods 11 and form the opposite sides of the parallelograms, will also oscillate by a periodic movement having the same period as the 60 movement of revolution of the entire wheel on the shaft 5.

It will be observed that in the case of a 65 lifting and propelling device adapted to travel in the air, the motion of the wings with reference to the air will produce upon

each wing a resultant pressure depending upon the law of oscillation of the wings. I may determine this law, as well as the characteristics of the wings and of their revolution about the central shaft, in such manner that this resultant will be vertical and will compensate for the total weight of the aircraft, whereby the latter will rise after the manner of a helicopter.

When the pilot considers the height to be 75 sufficient and desires to travel horizontally, he is enabled, by changing the amount and the direction of the eccentricity, to obtain another law of oscillation of the wings, such that the general resultant of the pressures 80 on the wings may be decomposed into a vertical component which sustains the apparatus and a horizontal component which causes it to advance in the proper direction at a forward speed which may be varied at will from 85 zero to the maximum speed.

Such an apparatus possesses great advantages over the known aircraft from the fact that it no longer requires special grounds for the starting and landing, and chiefly that the 90 horizontal speed in flight can be reduced, whereby a travel may be performed without danger during the night and in foggy weather, these being the most important obstacles to aerial navigation which remain to 95 be overcome.

Obviously, the said invention is not limited to the embodiment herein specified, this being given solely by way of example, and it is susceptible of numerous modifications 100 without departing from the principle of the invention. For instance, any desired number of wheels may be used, as also the number of wings or paddles on each wheel. The said wings may be given any suitable form. 105 The mechanism for rotating the wings may have a different construction from the one described. I may employ any suitable gear for varying the eccentricity of the discs with reference to the central shaft.

The said invention is applicable to any apparatus travelling in air or in any other fluid, and it may also be used as a source of power in a fluid in motion, said fluid rotating the wings or paddles of the wheel in order 115 to supply the desired power to the central shaft.

Having now described my invention, what I claim as new and desire to secure by Letters Patent is:

1. A turbine wheel for working in a fluid in relative motion thereto, comprising in combination a rotary member, a number of oscillating members pivoted to said rotary member about axes parallel to the axis of rotation of said rotary member, rigid members extending in a substantially radial direction and respectively pivoted to said oscillating members, cross-members respectively pivoted to said rotary member and to said rigid 125 members.

members, guide members rigidly secured to said cross-members respectively and rotary guiding means cooperating with said guide members respectively and whereby the axes of the latter are caused to constantly intersect at a single point.

2. A turbine wheel as claimed in claim 1, wherein said rotary guiding means comprise a number of independently loosely rotatable and concentrically arranged discs having radial extensions respectively, and means for slidably connecting said guide members with said extensions.

3. A turbine wheel for working in a fluid in relative motion thereto, comprising in combination a rotary member, a number of oscillating members pivoted to said rotary member about axes parallel to the axis of rotation of said rotary member, rigid members extending in a substantially radial direction and respectively pivoted to said oscillating members, cross-members respectively pivoted to said rotary member and to said rigid members, guide-members rigidly secured to said cross-members respectively, a number of independently movable guiding means cooperating with said guide members and adapted to rotate about a common centre and radially arranged relatively thereto, means for rotatably supporting said movable guiding means, and means for displacing said supporting means transversally, and for adjusting the position of said centre relatively to said axis of rotation.

35 4. A turbine wheel as claimed in claim 3, wherein said supporting means comprise a number of common rollers adapted to engage circular rolling tracks on said movable guiding means.

40 5. A turbine wheel for working in a fluid in relative motion thereto, comprising in combination a rotary member, a number of oscillating members having a main surface subjected to the dynamic reaction of the fluid, said members being pivoted to said rotary member about pivot axes parallel to the axis of rotation of said rotary member, rigid links extending in substantially radial directions and respectively pivoted to said oscillating members, right-angled levers pivoted to said rotary member on the straight line connecting said rotation axis to the corresponding pivot axis, one arm of said levers being pivoted to said link, whereby each 45 50 55 60 65 set comprising said link, said arm, said rotary member, and said main surface forms a deformable parallelogram, and rotary guiding means cooperating with the other arm of said right-angled levers respectively, whereby the axes of said other arms are caused to constantly intersect at a single point.

In testimony whereof I have signed my name to this specification.

CARL BRUNO STRANDGREN.
